CLAIM

The ornamental design for a personal massager, as shown and described.

DESCRIPTION

FIG. 1 is a right side perspective view of a personal massager showing my new design.

FIG. 2 is a front elevation view thereof.

FIG. 3 is a top side plan view thereof.

FIG. 4 is a bottom side plan view thereof.

FIG. 5 is a right plan view thereof.

FIG. 6 is a left plan view thereof.

FIG. 7 is a rear elevation view thereof.

FIG. 8 is a right side perspective view of a second embodiment thereof.

FIG. 9 is a front elevation view of the second embodiment thereof.

FIG. 10 is a top side plan view of the second embodiment thereof.

FIG. 11 is a bottom side plan view of the second embodiment thereof.

FIG. 12 is a right plan view of the second embodiment thereof.

FIG. 13 is a left plan view of the second embodiment thereof; and,

FIG. 14 is a rear elevation view of the second embodiment thereof.

The broken lines represent portions of the personal massager that form no part of the claim.
